UNITED STATES PATENT OFFICE.

CONRAD STEWART HENSLER, OF NORTH CHATTANOOGA, TENNESSEE.

DEVICE FOR CLOSING OPENINGS IN THE HULLS OF VESSELS BELOW THE WATER-LINE.

1,260,978.

Specification of Letters Patent. Patented Mar. 26, 1918.

Application filed July 20, 1917. Serial No. 181,849.

To all whom it may concern:

Be it known that I, CONRAD S. HENSLER, a citizen of the United States, residing at North Chattanooga, in the county of Hamilton and State of Tennessee, have invented new and useful Improvements in Devices for Closing Openings in the Hulls of Vessels below the Water-Line, of which the following is a specification.

10 This invention relates to a device which is primarily intended to be employed to prevent the sinking of vessels whose hulls have been penetrated by torpedoes, icebergs, or damaged by marine mines and the like, although the construction of the device is such that it may be employed to close the openings in receptacles of a different character if found desirable.

20 The primary object of the invention is to provide a device of this character which may be quickly applied to the vessel's hull to close the opening therein, and is so constructed that it may be guided into position for closing such opening by the current produced by the water entering the vessel's hull and maintained in place upon the hull of the vessel by water pressure.

25 With these and other objects in view, the invention resides in the novel construction and arrangement of parts, which will be hereinafter described and particularly pointed out in the claims.

30 The preferred embodiment of the invention has been illustrated in the accompanying drawings, although no restriction is necessarily made to the precise details of construction therein shown, as changes, alterations, and modifications within the scope of the claims may be resorted to when 35 desired.

In the drawings:

Figure 1 is a diagrammatical sectional view through the hull of a vessel and showing the plate for closing the opening in the 45 hull of the vessel being drawn into position by the current produced by the water entering the vessel's hull.

Fig. 2 is a view similar to Fig. 1 showing the plate held against the side of the vessel 50 by water pressure.

Fig. 3 is a plan view partly in section of a plate to be used in connection with the plate disclosed in Figs. 1 and 2 in the drawings.

55 Fig. 4 is a diagrammatical sectional view through the hull of the vessel showing the

plate disclosed in Fig. 3 in the drawings used in connection with the plate employed in Figs. 1 and 2 in the drawings.

Fig. 5 is a longitudinal sectional view 60 through a portion of the device.

Fig. 6 is a section on the line 6—6 of Fig. 5.

Fig. 7 is an enlarged detail sectional view 65 on the line 7—7 of Fig. 3.

Fig. 8 is a view in side elevation of the modification of the plate shown in Figs. 1 and 2 in the drawings.

Like characters of reference denote corresponding parts throughout the several views 70 in the drawings.

Referring now to the drawings in detail the letter A designates the hull of the vessel which has been penetrated below the water line and in Fig. 4 in the drawings the 75 opening in the hull of the vessel is shown closed by the device B.

The embodiment of the device includes a disk 10, constructed from any material suitable for the purpose, although I prefer to 80 form the disk from metal and provide the same with a slightly concave inner face 12 and a convex outer face 13 by which construction I obtain a feathered edge 14 at the periphery of the disk. In Fig. 5 of the 85 drawings, the disk 10 is shown composed of a plurality of superposed disk sections 15 which gradually decrease in diameter toward the outer face of the disk.

A compressible disk 16 of greater diameter than the disk 10 is adapted to contact with the inner concave face of the disk, while a flexible disk 17 of water proof material overlies the outer face of the disk 10 and extends a considerable distance beyond 95 the periphery of the disk 16 with the disk 17 gradually decreasing in thickness from its central portion until a feathered edge 18 is attained at its periphery. Suitable securing elements 19 connect the disks 16 and 18 with the disks 10 and also maintain the disk sections in superimposed relation. A flexible element 20 for lowering the disk 10 into the water from the side of the vessel as one terminal thereof is secured centrally 105 of the disk 17.

A cone 21 is arranged centrally upon the disk 16 and is provided at its base with a flange 22 through which the securing elements 19 are passed to secure the cone on the disk 10. The cone 21 has formed therein 110 adjacent its base a circumferentially extend-

ing row of spaced openings 23 through which a suitable securing element, such as a bar or the like, may be passed to act as a supplemental fastening means for retaining the disk 10 in applied position upon the hull of the vessel.

A flexible element 24 is connected at its inner end with an eye bolt 25 on the disk 10, and with the eye bolt extending beyond the apex of the cone. The element 24 has mounted thereon a plurality of cone shaped and spaced cups 26, which gradually increase in diameter from the outer end toward the inner end of the element 24. The cups 26 have arranged therein ears 27 with which the flexible element 24 is connected, said cups serving as means by which the current produced by the water entering the vessel's hull may guide the disk 10 in position to close such opening and to be held against the hull of the vessel by water pressure, the openings 23 in the cone 21 coacting with the cups 26 in accomplishing this result.

I desire to have it understood that I may make the disks 10 of different diameters if found desirable, so that if one of the disks 10 is not of a size sufficient to close the opening in the hull of the vessel, several of the disks may be employed for this purpose.

30 When the opening in the vessel's hull has cracks radiating therefrom I employ in connection with the disk 10 a plate 28, the side edges of which are beveled and with the plate having embedded therein a row of 35 transversely extending and spaced reinforcing rods 29.

Cables 31 are looped through suitable openings adjacent the corners of the plate 28 and may be employed to pass the plate 40 beneath the hull of the vessel and to maintain the same in place under the disk 10. The cables 31 have connected therewith grapples 32 which may be engaged with the frame work of the vessel to retain the plate 45 in place.

In Fig. 8 in the drawings the flexible element 24 which is connected with the cone 21 has mounted thereon a plurality of cups 33 which, like the cups 26 gradually increase in 50 diameter toward the disk 10 and are formed from suitable flexible water proof material.

The cups 33 are intended to be employed in the place of the cups 26 when the cargo of the vessel is such as to prevent the inrush 55 of water carrying the cups within the hold of the vessel and I find from experiment with cups constructed in this manner that the cups will become packed by the inrush of water between the cargo and the hull of the 60 vessel and frequently close the opening in the hull without the necessity of employing the disk 10 for this purpose.

When the hull of the vessel becomes punctured from any cause whatsoever the sailors 65 hang the flexible element 24 over the side of

the vessel, so that the inrush of water will carry the smaller of the cups through the opening in the vessel's hull, after which the disk 10 is thrown over the vessel's side and the cable 20 played out, to allow the inrush 70 of water to act upon the cups 26, or the cups 33 as the case may be, and carry the disk 10 against the side of the vessel and over the opening therein, in which position it is retained by water pressure.

With the disk held firmly pressed against the side of the vessel by the pressure of the water if found advisable a securing element 75 may be passed through the cone 21 through the openings therein and engaged with the hull of the vessel to retain the disk 10 in place. If the disk 10 is not of sufficient area to prevent the entrance of water into the vessel's hull the plate 28 is passed beneath the hull of the vessel to underlie the 85 disk 10 and the cracks in the hull of the vessel which extend beyond the opening.

From the foregoing description it is at once apparent that a device for closing openings in the hulls of vessels below the water 90 line has been provided which though inexpensive of manufacture is highly efficient for the purpose set forth.

Having thus described the invention, what is claimed as new is:—

1. In a device for closing openings below the water line in the hull of a vessel, a closure member adapted to be firmly held pressed by water pressure against the hull of a vessel to close an opening therein, a 100 plurality of cups connected with the closure member operable under the influence of water passing through said opening to guide the closure member into position to close the opening, and a flexible reinforced plate to 105 underlie said closure member and opening engageable with the vessel.

2. In a device for closing openings below the water line in the hull of a vessel, a closure member adapted to be firmly held 110 engaged with the hull of the vessel by water pressure to close the opening therein, a plurality of spaced cups connected to said closure member operable under the influence of water passing through said opening 115 to guide said closure member into position to close said opening, a flexible plate of water proof material adapted to underlie said closure member and the opening in the hull of the vessel, and means for retaining 120 said plate in applied position.

3. In a device for closing openings below the water line in the hull of a vessel, a closure member, a cone upon one side of 125 said closure member, and guiding means connected with said cone.

4. In a device for closing openings below the water line in the hull of a vessel, a closure member, a central apertured cone upon one side of the closure member, a flex- 130

ible element in advance of said cone connected with said closure member, and a plurality of spaced cups on the flexible element.

5. In a device for closing openings below the water line in the hull of a vessel, a flexible disk, a second disk arranged centrally thereon, an apertured cone arranged centrally of the second-mentioned disk, a flexible member extending beyond said cone and connected with said disk, and a plurality of spaced cups on said flexible member gradually increasing in size toward said cone.
10. In a device for closing openings below the water line in the hull of a vessel, a me-

tallic member having a concave inner face and a convex outer face, a disk of compressible material overlying the concave face of the metallic member and extending 20 beyond the periphery thereof, a second flexible disk of water proof material overlying the convex face of said member and extending beyond the periphery of first-mentioned disk, a central apertured cone on the 25 first-mentioned disk, a plurality of aligned open ended cups, ears within said cups, and a flexible member threaded through said cone and cups connected with said ears.

In testimony whereof I affix my signature. 30

CONRAD STEWART HENSLEE.
